BIMETALLIC ELECTRIC THERMOSTAT

Ernest A. Lowe, Fanwood, N. J., assignor to Aire-lease Corporation, Jersey City, N. J., a corporation of Delaware

Application December 4, 1937, Serial No. 178,185

7 Claims. (Cl. 200—138)

This invention has for its principal object the production of an exceedingly inexpensive and simple thermostatic device which shall be adapted to detect and give a visual or audible indication, by the energization of a signal or alarm, of the presence of excessive heat due, for instance, to a fire. By preference, the device may be detachably mounted on the ceiling of a room or other enclosure, the heated air naturally tending to flow upwardly, as is well known.

A further object of the invention is the production of a device of the above character which shall be so constructed as to occupy a very small space only.

A further object of the invention is the production of a thermostatic device having the above characteristics which shall be adapted to operate on the principle of the difference in the rate of expansion of two metallic strips or bars of different masses when they are subjected to the influence of heat. Accordingly, the device is peculiarly adapted in its application for the detection of a quickly acting fire where the temperature rises suddenly on what is known as the "rate-of-rise" of temperature principle in contradistinction to a gradual and more or less uniform rise in temperature and depending for operation on the attainment of a predetermined fixed temperature. The thermostat, however, is so constructed as to also be actuated upon the attainment of any predetermined fixed temperature and irrespective of its rate of rise.

By preference I utilize two coiled strips of planished metal which may be concentrically disposed with relation to each other in the interest of economy of space, one end of said strips being fixed and the other end thereof movable whereby the expansion of said strips by the action of heat and the consequent partial uncoiling of the strip will complete an electrical circuit which includes a signal and source of power and thereby energize the signal.

The planished metal strips employed preferably comprise two metals united by riveting or brazing to form bimetallic strips, one of said metals possessing a relatively high co-efficient of expansion and the other a relatively low co-efficient of expansion. When exposed to heat or temperature rise the metal having high expansive properties which may be any suitable metal or an alloy of metal, of necessity expands or lengthens while the other metal of which the metallic strip is composed and which may be brass, inasmuch as it has low expansive properties, will have little or no movement. The result

is a bending or uncoiling of the strip around a fixed point, such as the fixed end of the strip, in the specific embodiment of the invention illustrated. After expansion, and when the temperature again recedes, the high expansive metal automatically shrinks back to the contour it originally assumed. The thermostatic device may thus be said to be self-restoring so that the length of its life accordingly is indefinite.

A practical embodiment of the invention is illustrated in the accompanying drawing in which:

Fig. 1 is a plan view of the device showing the cover partly broken away to expose the contained parts a portion of which are shown in section.

Fig. 2 is a horizontal section taken through the device, and

Fig. 3 is an enlarged section taken through one of the bimetallic strips.

Referring in detail to the several figures of the drawing:

Either one of the bimetallic strips which, as shown in section in Fig. 3, are composed of two parts to wit: an outer strip of metal having high expansive properties and indicated at 10 and which may be composed of any suitable metal or an alloy of metal, and an inner strip 11 having low expansive properties which may be of any suitable metal such, for instance, as brass. These two strips are united together 30 preferably by riveting, brazing or welding to form complete units and the joined strips forming the units or elements are partially coiled and then heated so as to retain their coiled contour.

The two bimetallic strips or units are identical 35 in construction but the inner one, which is indicated at 12, is of relatively smaller width and mass than the outer bimetallic strip which is indicated at 13. The inner strip 12 accordingly is more susceptible to changes in temperature 40 than the outer bimetallic strip. The outer or heavier bimetallic strip is fastened at one end, as by a screw 14, to a block 15 of insulating material which forms a part of or is attached to an insulating base 16 comprising the support for 45 the thermostatic device of the invention. The base 16 is provided with a protective cover plate 17 having a plurality of perforations 18 to permit heated air to reach the thermostatic strips described. The cover 17 is suitably and detachably 50 fitted to the base 16 by the screws 19 shown.

An end view of the inner bimetallic coiled strip 12 or that of smaller mass is also secured to the block 15, as by the screws 10. The secured end 55 of said inner strip 12 may be provided with a con-

tact plate 20 and the inner side of the outer strip 13 adjacent its free end may be provided with a contact strip 21. A variable or adjustable contact screw 22 is carried by the free end of the outer strip 13 and is adapted to be brought into contact with the contact plate 20 while the free end of the inner bimetallic strip 12 carries a variable or adjustable contact screw 23 which is adapted to be brought into contact with the contact plate 21. One terminal of an electric circuit 24 is connected, as shown, to the fixed end of the bimetallic strip 12 while the other terminal is connected to the fixed end of the bimetallic strip 13. Said electrical circuit includes a battery 25 and a signal 26, either audible or visual, and of any suitable construction which is adapted to be energized when the circuit is closed. Obviously, however, the device may be operated either on an open or closed circuit by change of 10 the contact screws in the bimetallic strips 12 and 13.

The inner bimetallic strip 12 having the least mass and therefore being the most sensitive to changes in temperature is adapted to operate upon a sudden rate of rise of temperature occasioned, for instance, by the heat from a quickly acting fire. In that case the strip 12 tends to straighten out and consequently partially unwinds or uncoils in a counterclockwise direction 15 to thereby bring the end of the contact screw 23 into engagement with the contact plate 21 and thereby complete the circuit through the outer bimetallic strip 13 of heavier mass and in an obvious manner. When the operation of the device depends on the attainment of a fixed or predetermined temperature, however, occasioned for instance by a slow starting fire increasing gradually in intensity, both bimetallic strips will 20 expand or uncoil with approximate uniformity. In this case the circuit will be closed to energize the signal by the engagement of the end of the contact screw 22 with the plate 19, the circuit then being completed directly through the outer or heavier bimetallic strip 13 with the inner or 25 lighter bimetallic strip 12 forming no part of the circuit. As is obvious, when the bimetallic strips cool after being subjected to any heating effect, they contact and assume their original contour and position and at the same time break the circuit to de-energize the signal. The thermostat thus is a self-restoring one and may be used any number of times without adjustment and without replacement of parts. Furthermore coiling of the bimetallic units or elements and mounting them in concentric relation with respect to each other permits the device to be manufactured and installed in a conveniently compact and space-saving form. In practice I have found it feasible to construct the inner or smaller strip 12 of about 30 35 40 45 50 55 60 65 70 75

The invention claimed is:

1. An electric thermostat comprising two metallic coiled elements each consisting of two strips of metal united together one of which strips has a high coefficient of expansion while the other has a low coefficient of expansion, one end of each of said elements being free and the other end fixed and in circuit with a source of current supply and a signal with the free ends of each of said elements being movable and adapted to engage the

other element to close the circuit and energize the signal when said elements are subjected to the influence of heat, one of said elements being less than a full convolution thereby providing a gap between its ends and the other said element being greater than a full convolution and projecting through said gap of the first said element so as to make contact in operation at the inside of the first said element. 5

2. An electric thermostat comprising two coiled concentrically arranged metallic elements each consisting of two strips of metal united together, each said strip having appreciably different coefficients of expansion, one end of each of said elements being fixed and in circuit with a source of current supply and a signal and the other end of each element being movable and adapted to engage the other element to close the circuit and energize the signal when said elements are subjected to the influence of heat, one of said elements being less than a full convolution so as to provide a gap between its ends and the other said element being greater than a full convolution and having its movable end projecting through said gap of the first said element so as to make contact 10 15 20 25 30 35 40 45 50 55 60 65 70 75 80 85 90 95 100

3. An electric thermostat comprising two metallic coiled elements of different masses mounted in concentric relation to each other, said elements each consisting of two strips of metal united together one of which has a high coefficient of expansion while the other has a low coefficient of expansion, one end of each of said elements being fixed and in circuit with a source of current supply and a signal and the other ends of said elements being free and movable each toward the other element to close the circuit and energize the signal when said elements are subjected to the influence of heat, one of said elements being less than a full convolution thereby providing a gap 30 35 40 45 50 55 60 65 70 75 80 85 90 95 100

4. An electric thermostat comprising two strips of different masses the larger one of which is adapted to expand slowly in response to a gradual temperature rise and the smaller one of which is adapted to expand prior to the expansion of the larger strip when the thermostat is subjected to a sudden rate-of-rise of temperature, said strips being in circuit with a signal device and adapted for contact each with the other to close the circuit, one of said strips being arranged inside the other and provided with a gap and the other strip being provided with a free end extending through said gap adapted to contact with said first-named strip to close the circuit and energize said alarm when said second-named strip has reached a predetermined temperature. 50 55 60 65 70 75 80 85 90 95 100

5. An electric thermostat provided with a support and two coiled metallic elements of different masses mounted on said support and each comprising two strips of metal united together, each said strip having appreciably different coefficients of expansion, one end of each of said elements being fixed and in circuit with a source of current supply and a signal and the other ends of the elements being free and each adapted to close toward the other and thereby in either event close said circuit and energize said signal upon a rise of temperature, one of said elements being less than a full convolution thereby providing a gap 70 75 80 85 90 95 100

ing greater than a full convolution and projecting through said gap of the first said element so as to make contact in operation at the inside of the first said element.

6. An electric thermostat provided with a base having an upstanding block and two metallic coiled elements of different masses mounted on said block in concentric relation to each other, said elements each comprising two strips of metal united together one of which has a high co-efficient of expansion while the other has a low co-efficient of expansion, one end of each of said elements being secured to said block on opposite sides thereof and in circuit with a source of current supply and a signal and the other ends of said elements being free and movable each toward the other element to close the circuit and energize the signal when said elements are subjected to the influence of heat, one of said elements being less than a full convolution thereby providing a gap between its ends and the other said element being greater than a full convolution and projecting through said gap of the first said element so as to make contact in operation at the inside of the first said element.

7. An electric thermostat provided with a base, an insulating block mounted thereon, a removable perforated cover detachably mounted on said base and two metallic coiled elements of different masses concentrically positioned within said cover, said elements each comprising two strips of metal united together one of which strips has a high co-efficient of expansion while the other has a low co-efficient of expansion, one end of each of said elements being free and the other end secured to said insulating block and in circuit with a source of current supply and a signal with the free ends of said elements being movable and adapted to engage the other element to close the circuit and energize the signal when said elements are subjected to the influence of heat, one of said elements being less than a full convolution thereby providing a gap between its ends and the other said element being greater than a full convolution and projecting through said gap of the first said element so as to make contact in operation at the inside of the first said element.
